FOUNTAIN

Virgil C. Camp, 3749 Cornell,
Des Moines, Iowa 50313

Filed Oct. 11, 1972, Ser. No. 296,662

Term of patent 14 years

Int. Cl. D23—01

U.S. Cl. D23—13

Fig. 2

Fig. 1

Fig. 3

FIG. 1 is a side elevational view of a fountain showing my new design, the opposite side being a mirror image of the side shown;

FIG. 2 is a top plan view of the hood portion thereof; and

FIG. 3 is an enlarged top plan view of the base portion thereof.

I claim:

The ornamental design of a fountain, substantially as shown and described.
